UNITED STATES PATENT OFFICE.

ALBERT W. CONNOR, OF COVINGTON, KENTUCKY, AND GEORGE D. ANDERSON, OF CINCINNATI, OHIO, ASSIGNEES TO THE CINCINNATI AUTO SPECIALTY CO., OF CINCINNATI, OHIO, A CORPORATION OF OHIO.

RADIATOR-COVER.

1,354,889.

Specification of Letters Patent.

Patented Oct. 5, 1920.

Application filed April 30, 1918. Serial No. 231,707.

To all whom it may concern:

Be it known that we, ALBERT W. CONNOR, a citizen of the United States, and residing at Covington, in the county of Kenton and

5 State of Kentucky, and GEORGE D. ANDERSON, a citizen of the United States, and residing at Cincinnati, in the county of Hamilton and State of Ohio, have invented a new and useful Improvement in Radiator-Covers, of which the following specification is a full disclosure.

Our invention relates to a cover for an automobile radiator hood.

The object of the invention is to produce 15 a relatively inexpensive, one-piece cover, conveniently applied or removed, and affording efficient weather protection.

The material is of any approved water-proof fabric, made of double-ply, suitably 20 interlined and stitched.

The features of the invention are more fully set forth in the description of the accompanying drawings, forming a part of this specification, wherein:—

25 Figure 1 is a plan view of the cover.

Fig. 2 is a front view, showing the cover applied.

Fig. 3 is a plan view of the one-piece outline and cutting.

30 The cover is originally cut out of a blank in the contour shown in Fig. 3, having the major shield-shape portion 1, and the upper extension portion 2, the opposite side edges 3, of which diverge from the rounded 35 edges 4 of portion 1, and portion 2 has the rounded extremity 5.

The medial lower portion of member 1 is cut out to form the opening 6 to accommodate for the overlap of the radiator-opening 40 curtain 7, which is provided by the slits 8, running down convergingly from the covers 9, defining the division between portions 1 and 2. These converging slits 8 run down to the cut-out portion 6 and form the said 45 curtain 7, and, of course, formed in a single cutting operation.

The upper portion of this one-piece member 1, 2, is folded upon itself, that is, member 2 is dropped down upon member 1, till 50 the corner points 10, of member 2, overlap member 1, the entire cover having now the shield-shape shown in Fig. 1, and the curtain 7 completely covers the radiator-hood opening area, and the marginal edges 3 of

the curtain 7, overlap the margins of the 55 portion 1, covering the radiator ventilating opening, defined by dotted lines 13, Fig. 1, and secured at the bottom by snap 14.

The parts are stitched on the line where the points 10 of member 2 overlap member 60 1, thus defining the line of curtain securance, indicated by dotted line 15, Fig. 1.

The cover is provided with the belt 16 on its underside for strapping over the water-nozzle of the radiator-hood.

The portion of the cover shown covers the radiator-hood front, and to the margins of this is secured a perpendicular flap to overlap the top and sides of the radiator-hood, constituting the usual hood-structure. 70

The material as well as the operations are economical, the structure simplified, and a very warm, snug, durable and convenient cover is thus provided.

Having described the invention, we 75 claim:—

1. The herein described method of forming a radiator front covering, comprising a body portion, having a central opening and a curtain portion for the body opening, consisting in cutting said members from an integral blank, by cutting the blank inwardly from opposite sides toward one end along lines joining and representing three sides of an isosceles trapezoid, dividing the blank into a body member having a central cut-out opening and a curtain member corresponding to the outline of the body opening, reducing the length of said curtain member and securing the members 80 together with the curtain edges overlapping the opening edges of the body.

2. The herein described method of forming a radiator front covering comprising a body portion having a central opening and a curtain portion for the body opening consisting in cutting said members from an integral blank by cutting the blank inwardly from opposite sides toward one end along lines joining and representing three sides of an isosceles trapezoid, dividing the blank into a body member having a central cut-out opening and a curtain member corresponding to the outline of the body opening, and securing the members together with 85 the curtain edges overlapping the opening edges of the body.

3. The herein described method of form-

ing a radiator front covering comprising a body portion having a central opening and a curtain portion for the body opening consisting in cutting said members from an 5 integral blank of suitable outline, cutting the blank along lines dividing the blank into a body member having a central cut-out opening and a curtain member corresponding to the outline of the body opening, and 10 securing the members together with the curtain edges overlapping the opening edges of the body.

4. In a radiator covering comprising a body member having a central opening, and 15 a cover member for said opening similar in outline to the opening, said cover member

cut from a single blank member, the cover member representing the material cut to provide the central opening of the body member and of reduced length and secured 20 to said opening end of said body with its edges overlapping the opening edges of the body.

In witness whereof, we hereunto subscribe our names, as attested by the two subscrib- 25 ing witnesses.

ALBERT W. CONNOR.
GEORGE D. ANDERSON.
